EMIL KROHN AND VICTOR A. LILLQUIST, OF DULUTH, MINNESOTA, ASSIGNEES OF ONE-
THIRD TO AXEL W. BJORKLUND, OF MINNEAPOLIS, MINNESOTA

DOOR-OPERATING DEVICE

Application filed June 27, 1927. Serial No. 201,902.

This invention relates to a door operating mechanism, and while the invention is applicable to many types of doors, it particularly is designed to operate such a door as a garage door, especially a private garage. It is a very common practice for drivers to have a garage at their residence, and it is generally desirable to have the garage door shut when the driver is out with the automobile. When the driver returns to the garage, it is often necessary for him to get out of the automobile to open the garage door and then to again enter the automobile to drive the same into the garage.

It is an object of this invention, therefore, to provide a simple and easily operated mechanism by which the driver can open the garage door without getting entirely out of the automobile.

It is another object of the invention to provide such a device comprising an operating mechanism, preferably of the lever type, disposed some distance in front of the garage, connected to a door operating mechanism adjacent the garage door, which includes a flexible or articulated member disposed in a guide member and which is connected to the door.

It is also an object of the invention to provide a door operating mechanism such as set forth in the preceding paragraph, together with a locking mechanism for the door which is released by the movement of said lever prior to the opening movement of the door.

These and other objects and advantages of the invention will be fully set forth in the following description made in connection with the accompanying drawings, in which like reference characters refer to similar parts throughout the several views and in which:—

Fig. 1 is a transverse vertical section through the building, showing the inner side of the doors with the mechanism applied thereto; said section being taken on line 1—1 of Fig. 2;

Fig. 2 is a horizontal section of the building taken substantially on line 2—2 of Fig. 1;

Fig. 3 is a horizontal section taken on line 3—3 of Fig. 2;

Fig. 4 is a partial horizontal section such as shown in Fig. 2 shown on an enlarged scale, with certain parts broken away;

Fig. 5 is a partial view in plan of the flexible or articulated member used;

Fig. 6 is a vertical section on line 6—6 of Fig. 5;

Fig. 7 is a view similar to Fig. 3 showing a modified construction;

Fig. 8 is a vertical section taken on line 8—8 of Fig. 7;

Fig. 9 is a partial view similar to Fig. 7 showing a modified form of construction;

Fig. 10 is a vertical section on line 10—10 of Fig. 11; and,

Fig. 11 is a horizontal section taken on line 11—11 of Fig. 10, said figures showing a modification, all of said sections being taken as indicated by the arrows.

Referring to the drawings, in Figs. 1 and 2 a building such as a garage building is shown, comprising the vertical walls 10 having the roof 11, the front wall 10^a and the 75 oppositely swinging double doors 12 and 12^a. The hinges for the doors are shown as 13. The door 12 has secured thereto an inwardly extending bracket 14 to which is pivoted a link 15, in turn pivotally connected at its other 80 end to a lug or bracket 16 secured to the inner side of the door 12^a. Another bracket 17 is secured to the inner side of door 12^a, one end of which projects into the channel or guideway of a guide member 18. The guide 85 member 18 is secured to the floor and projects through the front wall 10^a of the building, having its outer end 18^a projecting outward from said wall substantially perpendicular thereto and having its inner end 18^b reversely 90 curved as shown in Figs. 2 and 4 toward the free edge of the door 12^a. A flexible or articulated member 19 is disposed within the channel or chamber in member 18 and while this member may be variously formed, in 95 the embodiment of the invention illustrated it is shown as comprising the pivotally connected and spaced links 19^a connected by the rivet pins 19^b on which are journaled the spaced rollers 19^c. The rollers 19^c engage 100

the sides of the channel or the inner walls of member 18. The end pivot pin 19^a of member 19 is extended to one side of the links 19^a and extends through the end of bracket 17, being secured thereto by a suitable nut. The member 19 has connected to the pivot pin at the other end thereof a hub or boss of the rod 20 which extends through the end of member 18 and through a housing conduit 21. The housing conduit 21 is secured at its other end to the wall of a rectangular casing 22 disposed some distance at the outer side of the garage and at the front thereof. The casing 22 has a hinged top 22^a hinged along one longitudinal side thereof. Said lid may be provided with a hasp 22^b extending over a staple 22^c and locked in closed position by a lock 22^d. A shaft 23 extends across the casing 22 having its ends journaled in the side walls thereof, which shaft has secured thereto an arm 24. The arm 24 has pivotally connected to its outer end a link 25, the other end of which is pivotally connected to the rod 20. The arm 24 has a portion 24^a connected thereto through which slidably extends a lever 26 carrying a stop pin 27. The casing 22 has an aperture 22^a in the bottom thereof adapted to receive the end of a lever 26, at certain times. The doors 12 and 12^a overlap at their meeting point as shown at 12^b. A locking mechanism is provided for the door 12^a and while this mechanism may be of various forms, in the embodiment of the invention illustrated it is shown as comprising a bolt 28 slideable in a casing 29 and urged by a spring (not shown) into engagement with a keeper 30 disposed above the doors. The bolt 28 is of the type having an inclined edge which will spring into engagement with the keeper 30 when the door is closed. The bolt 28 has an eyelet at one end to which is connected a flexible cord or cable 31 running over a pulley 32 mounted on the inner side of the door 12^a and also over a pulley 32 mounted in a bracket 33 secured to the door post 10^b. The cord 31 passes from the pulley 32 over another pulley 34 mounted in a bracket 35 secured to the wall 10 and said cord 31 extends downward from pulley 34 and runs over another pulley 36 mounted in a bracket 37 also secured to the wall 10, said cord passing from pulley 36 into a tube 38 extending through the front wall 10^b, which tube connects at its outer end to the end of the member 18, the cord 31 passing through the end of member 18 and through the conduit 21. The cord 31 passes through the other end of conduit 21 over a pulley 38 mounted in a bracket 39 secured to the end wall of the casing 22 and thus over a pulley 40 mounted in a bracket 41 also secured to the end wall of casing 22. From pulley 40 the cord 31 extends to and is connected to an apertured lug 26^a adjacent the end of lever 26.

In operation, when the doors 12 or 12^a are closed, they will be in the position shown in Figs. 1 and 2. When the driver wishes to open the doors and drive the automobile into the garage, he will drive the car up to the front of the garage so that the same is close alongside of the casing 22. The casing 22 is of a height to come somewhat above the running board of the automobile. The driver can reach down and open the lid of the casing 22 and swing lever 26 upwardly. The lever is first pulled through the member 24^a until the pin 27 engages the same and is then swung to vertical position. When in this position, the lever can be pushed downwardly into the opening 22^a so that it will be held in vertical position. When the lever 26 is pulled lengthwise, it pulls upon the cord 21. This cord moving over the various pulleys, pulls downwardly on the bolt 28, thus unlocking the doors. When the lever 26 is swung upwardly, arm 24 is swung and through the link 25 pushes the rod 20 lengthwise into the conduit 21. This pushes the member 19 through the guide member 18, the same being guided by the rollers 19^c. This causes a movement of bracket 17 outwardly, thus swinging the door 12^a open into the position shown in dotted lines in Fig. 2. This movement of door 12^a through the link 15 in bracket 14 also swings open the door 12 so that the doors take the position shown in dotted lines in Fig. 2. The doors being so open the driver can now drive into the garage. The lever 26 can be operated by the driver without entirely getting out of the car and it is not necessary for him to walk to the garage and open the doors. After the car is in the garage, the driver leaves the same as usual and he can then shut the doors by an opposite movement of the lever 26 moving the same to the position shown in Fig. 3. As the door is closed, the bolt 28 will engage the keeper 30 and the doors will be locked in closed position. The lid 22^a may then be closed and the lock 22^d applied so that the doors cannot be opened by unauthorized parties.

In the structure shown in Figs. 7 and 8, the link 25 which is connected at one end to the rod 20 is pivotally connected at its other end to the end of a segmental gear arm 45 secured to a shaft 46 journaled in the walls of the casing 22. The segmental gear arm 45 has its gear portion meshing with a gear 47 mounted on a shaft 48 also extending between and journaled in the walls of the casing 22, which gear 47 has a portion 47^a through which slidably extends a lever 49 having a stop pin 50 adjacent its lower end to which lever is connected adjacent its other end the cord 31 already described.

The operation of the structure shown in Figs. 7 and 8 is substantially the same as that already described. The operator will lift the lid 22^a and move the lever 49 longitudinally,

thus pulling on the cord 31 and releasing the locking means 28. The lever 49 will thus be swung to vertical position as indicated in dotted lines in Fig. 7 and its end engaged in the opening 22°. This swinging movement of the lever will turn gear 47, which in turn will oscillate the arm 45 and move link 25 toward the rod 20. This rod will, as already described, operate the member 19 and bracket 17 to open the doors. The doors will be closed by an opposite movement of the lever 49.

In Fig. 9 the cable 31 is illustrated as connected to an eyelet 51 secured in the lid 22a. In this structure the operating lever for the rod 20 need not be arranged to be moved longitudinally, but will simply be swung to push or pull on the rod 20. As the operator raises the lid 22a, the cable 31 will be pulled upon and the lock 28 released. If the driver desired, he could simply swing the lever 26 or 49 to open the doors and need not place the lid in the recess 22° to hold the same in vertical position. The lever can be left in position so that the lid 22a can be closed and locked. After entering the garage, the operator could then close the doors by hand and this movement would move the lever 26 or 49 to its position shown in full lines in Figs. 3 and 7 respectively. Such a method would be preferable where there was an exit from the garage other than the doors, as when the garage is in a basement and the driver would wish to go from the garage or basement to the upper floors without going out through the doors.

In Figs. 10 and 11 another modified form of operating means is shown for the device. In said figures the casing 52 is shown having a base portion 52a and an upstanding conical column 52b. The base portion 52 has lugs 52c projecting therefrom adapted to receive securing bolts 53 which will secure the device to a suitable supporting surface 54. The column 52b has a semi-spherical or bowl-shaped portion 52d at its upper end to which is hinged a semi-spherical cover 52e, said portions 52b and 52e forming substantially a ball. Said portions have co-operating lugs receiving the hinge pin 55, and have co-operating lugs at the other side adapted to receive a barrel 56 of a tumbler lock, whereby the portions 52e and 52d may be locked together or in closed position. The base portion 52a also has at one end a projecting boss 52f illustrated as threaded to receive the end of a conduit 21 already described, said conduit receiving the rod 20, the end of which projects into member 52. Said rod is connected to a bar 57 having regularly spaced holes 57a extending therethrough. The member 52 has a bar 52g extending thereacross at its bottom, having projecting lugs in which are secured short shafts 58 having journaled thereon rollers 59 against which one side of bar 57 bears. A shaft 60 is provided, ex-

tending centrally of column 52b, said shaft having its lower end journaled in an aperture in member 52g, said shaft 60 carrying a pinion 61. The teeth of pinion 61 are arranged to engage in the apertures 57a of bar 57. The shaft 60 has secured at its upper end a member 62 having lugs in which a pivot pin 63 is secured, forming the pivot of crank handle 64 adapted to be swung into the position shown in full lines in said figure, or when top 52a is opened, in the position shown in dotted lines.

In operation the member 52 will be disposed a suitable distance in front of the garage door and will be about three feet six inches high, so that the same can be conveniently operated by the driver of a car without leaving the car. The driver will drive alongside the member 52 and will unlock 56 and open the cover 52e. He will then swing crank 64 to the dotted line position and will rotate the same. This will rotate shaft 60 and pinion 61 and move bar 57 longitudinally, thus pushing on rod 20 and opening the doors as already described. When the device is closed and locked, the crank 64 is disposed as shown in full lines in Fig. 10. When the member 52 is used, the cable 31 will be attached to the lid 52a and will open the lock as described in connection with Fig. 9.

From the above description it is seen that applicants have provided an extremely simple and easily operated device by means of which the doors of a garage or other building may be opened at some distance therefrom and without the driver of an automobile getting out of the car and walking to the doors. The device forms a very convenient means for operating the doors, especially in rainy or stormy weather. The parts of the device are quite few and simple and can be easily and inexpensively made and installed.

It will, of course, be understood that various changes may be made in the form, details, arrangement and proportions of the parts, without departing from the scope of applicants' invention, which, generally stated, consists in a device capable of carrying out the objects above set forth, in the novel parts and combinations of parts disclosed and defined in the appended claims.

What is claimed is:

1. A door operating device having in combination with a wall, and a pair of oppositely swinging doors hinged thereto, a bracket secured to one of said doors and projecting inwardly therefrom, a link connecting said bracket to the other door, a bracket secured to said last mentioned door, a guide member extending through said wall adjacent the pintle axis of said last mentioned door and having its inner end curved toward the free end of said doors when in closed position, said guide member having a guide channel therein, a flexible member comprising freely revoluble

spaced rollers connected together by freely swinging links extending through said guide channel, a bracket secured to said last mentioned door having an end thereof extending into said guide channel and secured to one end of said flexible member, and manually operated means disposed at some distance from said door at the outer side thereof connected to said flexible means for pulling and pushing upon the same for closing and opening said doors respectively.

2. A door operating mechanism comprising a casing, an oscillating shaft in said casing, a rod extending into said casing, adapted to be pulled or pushed upon to close or open said door, a flexible member extending into said casing adapted to be pulled upon to unlock said door, a swinging arm in said casing to which said rod is connected, a hand lever for swinging said arm, said lever being also longitudinally movable, and a recess in said casing into which the end of said lever may be moved to hold the same in position after being longitudinally moved and swung to open said door.

3. The combination with the wall of a building and a swinging door disposed substantially in the plane of said door when in closed position, a guide member extending through said wall at one side of the pintle axis of said door, said guide member being curved to have its inner end directed toward the free edge of said door, a bracket secured to said door and having one end extending into said guide member, a chain comprising links and rollers journaled therein disposed in said guide member and connected at its inner end to said bracket, a rod connected to the other end of said chain and extending some distance to the front of said door at the outer side thereof, and means for reciprocating said rod to open and close said door.

4. A door operating mechanism comprising a casing, a shaft mounted for turning movement in said casing, a rod extending into said casing adapted to be pulled or pushed upon to open or close said door, means for guiding said rod for longitudinal movement in said casing, a lever in said casing comprising a pivoted handle portion operatively connected to said shaft for turning the same, a cover for said casing, said lever being adapted to be disposed in one position with the cover closed, and to project from said casing in operative position when the cover is swung to open position.

5. A door operating device having in combination with a swinging door, a bracket secured to said door, a guide member disposed adjacent the axis about which the door swings and extending from the inner to the outer side of said door, a flexible member disposed in said guide member, a push and pull rod connected to said flexible member and extending some distance from the door at the outer side

thereof, a casing, a lever adapted to be received in said casing and connected to said rod for pushing and pulling on the same and moving said flexible member whereby said door is opened or closed, a locking means for said door, a cable secured to said locking means and movable with said flexible member and rod by said lever when the door is opened, to release said locking means.

In testimony whereof we affix our signatures.
